UNITED STATES PATENT OFFICE.

CHARLES L. DEPOLIER, OF BROOKLYN, NEW YORK.

FINGER-RING.

1,245,201.

Specification of Letters Patent.

Patented Nov. 6, 1917.

Application filed June 29, 1917. Serial No. 177,633.

To all whom it may concern:

Be it known that I, CHARLES L. DEPOLIER, a citizen of the United States, and residing in the borough of Brooklyn of the 5 city of New York, county of Kings, in the State of New York, have invented certain new and useful Improvements in Finger-Rings, of which the following is a specification, reference being had to the accompanying drawing, forming a part hereof.

This invention relates to multiple finger-rings in which two complete annuli, secured together at one point and held in parallel relationship by a seal or signet or setting, 15 receive snugly between them a third annulus which is held in place between the other two annuli by friction. Such rings have had and still have somewhat of a sentimental vogue, the middle annulus being 20 a wedding-ring or a pledge-ring guarded by the two outer annuli. The purpose of this invention is to improve the construction of rings of this character so as to give them not only a sentimental usefulness but 25 a practical usefulness in the way of identification of the wearer. In accordance with the invention the middle member is an incomplete annulus and receives between its ends a pivoted member which can be turned 30 into the plane of the middle ring member so as to be introduced between the two outer members, and may then be swung upon its pivot to a position at right angles to the plane of the middle member so as to enter 35 the signet or bond by which the two outer members are held together. This pivoted member may be solid and may receive initials or symbols engraved upon its two faces, or it may be formed with a chamber to receive 40 a memento such as a lock of hair, or to receive a stone. The signet or bond of the two outer members may have a continuous wall to cover and hide the pivoted member or it may have an aperture to dis- 45 close the pivoted member. The invention will be more fully explained hereinafter with reference to the accompanying drawing in which it is illustrated and in which,—

Figure 1 is a view of the improved ring 50 in diametrical section.

Fig. 2 is a view of the same elevation, with three ring members concentrically arranged.

Fig. 3 is a view similar to Fig. 2 but with

the middle ring member drawn partly out 55 of place and its pivoted member swung into the same plane.

Figs. 4 and 5 are views of the ring as seen from above in Fig. 2, but with the pivoted member swung so as to show different faces 60 in the two views.

Fig. 6 is a view similar to Fig. 1 but showing a modification.

Fig. 7 is a view in section on the plane indicated by the line 7—7 of Fig. 6, looking 65 in the direction of the arrows.

Fig. 8 is a view similar to Fig. 3 but showing the modified form.

Fig. 9 is a view similar to Fig. 4 but showing the modified form. 70

Fig. 10 is an edge view of the ring shown in Figs. 6—9.

In the several embodiments of the invention shown in the drawing the improved ring includes as heretofore two outer ring 75 members or annuli *a* and *b* united at one point and held in parallel relationship by a signet or bond. In the construction shown in Figs. 1—5 this signet or bond *c* is frame-like or has an open center. The middle 80 ring member *d*, which is an incomplete annulus, has pivoted between its ends, as at *d'*, a receiver or pivoted member *e* which, in the construction shown in Figs. 1—5, is represented as a solid member and as receiving 85 on one face an initial and on the other face a symbol. This pivoted member or receiver *e* has at its ends stops *e'* which are adapted to engage stop shoulders *c'* formed on the bond *c* for the purpose of holding the pivoted member *e* truly parallel with the bond *c* when the ring member *d* is pressed home. It will be observed that the receiver *e* has a thickness no greater than the width of the space between the outer ring members, so 90 that when the ring member *d* has been partly withdrawn and the receiver *e* has been turned into the same plane therewith, as represented in Fig. 3, the ring member and receiver can be completely withdrawn and 95 replaced as desired. When the ring members are in the relative positions represented in Fig. 3 the receiver *e* can be turned to expose one face or the other within the bond *c*.

100 The construction shown in Figs. 6—10 is substantially the same as that already described including the two outer ring mem-

bers α and β and the middle ring member d , but the bond c^2 is shown in this instance as having a solid or continuous face and the pivoted member or receiver e^2 is formed as a container adapted to receive a memento, such as a lock of hair. In this instance the contents of the receiver e^2 are concealed at all times by the bond c^2 , but the middle ring member with the receiver can be withdrawn 10 at any time by first partially withdrawing the middle member and then turning the receiver into the same plane therewith so that, having a thickness no greater than the width of the space between the two outer 15 ring members, it may be withdrawn completely.

It will be obvious that the invention is capable of embodiment in rings of many different designs. It has been sought here- 20 in to illustrate such embodiments as will suffice to exhibit the character of the invention.

Copies of this patent may be obtained for five cents each, by addressing the "Commissioner of Patents, Washington, D. C."

I claim as my invention:

1. A finger-ring comprising two outer ring members, a bond uniting them, a middle ring member forming an incomplete annulus, and a receiver pivoted between the ends of the middle ring member. 25

2. A finger-ring comprising two outer ring members, a bond uniting them, a middle ring member forming an incomplete annulus, and a receiver pivoted between the ends of the middle ring member, the bond being formed to receive the pivoted member. 30

3. A finger-ring comprising two outer ring members, a bond uniting them, a middle ring member forming an incomplete annulus, and a receiver pivoted between the ends of the middle ring member, the bond being formed as a frame to receive and dis- 35 close the pivoted member.

This specification signed this 25th day of June A. D. 1917.

CHARLES L. DEPOLLIER.
